UNITED STATES PATENT OFFICE.

DAVID M. GREAR, OF CHICAGO, ILLINOIS.

COAL-CAR COVER.

1,291,481.

Specification of Letters Patent.

Patented Jan. 14, 1919.

Application filed August 8, 1918. Serial No. 248,929.

To all whom it may concern:

Be it known that I, DAVID M. GREAR, citizen of the United States, residing at Chicago, in the county of Cook and State of Illinois, have invented certain new and useful Improvements in Coal-Car Covers, of which the following is a specification.

This invention is a coal car cover and has for its principal object the production of a device which will prevent the unauthorized access to the coal within the car.

Another object of this invention is the production of a coal car cover wherein a plurality of the hinged sections are carried by the car body to fit over the coal carried by the car to prevent unauthorized access thereto.

Another object of this invention is the production of a coal car cover wherein the sections may be swung open to positions to allow access to the interior of the body by an authorized party.

Another object of this invention is the production of a coal car cover wherein the hinged sections are hood-like in construction to fit over coal within the body which may be stacked above the top of the car, the sections also being provided with flat tops to provide a walk to allow a trainman to walk therealong, while the guards extend longitudinally of the sections and prevent the trainman from accidentally falling from the cover when walking therealong.

One practical form of construction and assembly of the present invention will be hereinafter described and is illustrated in the drawing, in which—

Figure 1 is a side elevation of the coal car cover showing the same mounted upon a car body.

Fig. 2 is an end elevation of the car cover, in a closed position, and

Fig. 3 is a central transverse section through the cover in a closed position, a portion of the car body being shown in fragmentary section.

In the preferred embodiment of the invention, which is herein illustrated, it will be noted that a coal car is indicated in general at 5 having the usual dumping arrangement indicated in general at 6. As is well known, these coal cars generally now in use, are open at their upper portions and for this reason on sidings they are often robbed of their contents.

In order to overcome this objection, the

present invention may be employed. The hinged sections which form the present invention are similarly constructed and comprise back walls 7 having end walls 8. The back walls and end walls are also provided with flat tops 9. It will be noted that the back walls 7 of the hinged sections slant upwardly and for this reason each hinged section comprises a hood like structure, as it is substantially concaved in cross section, as illustrated in Fig. 3.

The brackets 10 are provided with off-set ends and are fixed upon the body 5, as illustrated in Fig. 3. The leaf sections 11 are fixed upon the back walls 7 of the sections and are hingedly connected to the bracket portions 10 as indicated at 12, thus hingedly connecting the hinged sections to the car body.

It will be noted that a completed section is substantially one-half the width of the car body, although it extends longitudinally of the car body throughout its entire length. Therefore, when the two sections are in a closed position as indicated in the several figures of the drawing, the sections will fit over the coal carried within the car body 5, even though this coal may be stacked above the upper portion of the car body, thus shielding the same from access thereto. It is obvious that a hasp 13 may be connected to one end wall of the hinged sections at each end of the car, and may be retained in engagement with the remaining end wall by a connection as indicated at 14, which may be a pad lock or a plug retained by the usual seal for car doors. Therefore, it will be seen that the cover will be held in closed position.

When access is desired to the interior of the car body 5, it is obvious the sections may be unlocked and then swung to open positions, and at this time, they will rest upon the side surfaces of the car, fitting very close thereto, so as not to interfere with a passing car when the sections are in open positions.

Vertically extending walls 15 are formed on the sections adjacent the junction of the flat tops 9 and the slanted backs 7. It will be noted that these vertical walls 15 extend longitudinally of the sections and are of the same length as the sections. Therefore, when the sections are in closed position, two of such vertical walls are parallel, as illustrated in Figs. 2 and 3. As the tops 9 are flat, they will extend in alignment with each

other to provide a flat walk or run-way, to allow a trainman to walk along the top portions of the closed sections, while the walls 15 will prevent the trainman from accidentally walking from the top or slipping 5 from the upper portions of the sections. Instead of providing the solid walls 15 as herein illustrated, it is obvious that vertical posts may be carried at the ends of the sections and be connected by a railing for accomplishing this function, although by having the walls solid, it is obvious that if the flat tops 9 are slippery and the trainman should happen to slip, it will be impossible 10 for him to slip under the walls and be thrown from the top of the closed sections.

It will therefore be seen that a very simple and efficient cover has been provided for preventing unauthorized access to the 20 interior of the car when the covers are in closed positions, although the sections may be swung to open positions to allow free access to the interior of the car, if so desired by an authorized party. It will be noted 25 that the construction of the sections is such that when in a closed condition, they will fit over coal which may be stacked above the upper portions of the car body, while the flat tops provide an efficient walk or run- 30 way for the trainman to pass over, and the guards at the side portions of these flat tops for preventing the trainman from being thrown or from passing accidentally to one side and from the top of the cover, 35 while the train is in motion.

The foregoing description and the drawings have reference to what may be considered the preferred, or approved, form of my invention. It is to be understood that I 40 may make such changes in construction and arrangement and combination of parts, materials, dimensions, et cetera, as may prove expedient and fall within the scope of the appended claims.

Having thus described my invention, what I claim as new and desire to secure by Letters Patent, is:—

1. In a device of the class described, the combination of a car, covers hingedly mounted upon said car, and vertically extending walls carried by said covers and ex-

tending longitudinally thereof, whereby said walls will extend parallel to each other, thus preventing a trainman who is walking or standing between the walls from slipping 55 and falling beyond either side of the car.

2. In a device of the class described, the combination of a car, covers hingedly mounted upon said car, said covers comprising slanting back walls having flat tops, the back wall and top of each cover having end walls, thus forming concaved covers, and a guard means carried by each cover at the junction of the backs and flat tops thereof, whereby the guard means will be in parallel 60 arrangement when the covers are in an operative position, thus preventing a trainman from being thrown or walking from either side of the flat tops.

3. In a device of the class described, the combination of a car, covers hingedly mounted upon said car, each cover comprising a slanting back having a flat top, end walls connecting the flat top and back of each section to form a hollow structure, and vertically extending walls formed on said covers at the junction of the slanting backs and the flat tops, whereby a trainman may walk freely along the flat tops and may perform the usual functions, without 80 danger of being thrown or slipping from the covers to fall beyond either side of the car.

4. In a device of the class described, the combination with a box car having an open 85 top; of a cover therefor made in two sections whereof each has an inclined back wall hinged at its lower edge to the upper edge 90 of the side of the car-body, upright end walls adapted to contact with the upper edges of the ends of the car body when the section is closed, and a flat top, said tops standing edge to edge when the cover sections are closed, and upright walls along the outer edges of said tops, for the purpose 95 set forth.

In testimony whereof I affix my signature in presence of two witnesses.

DAVID M. GREAR.
